UNITED STATES PATENT OFFICE.

GUILLIAM H. CLAMER AND CHARLES F. HOPKINS, OF PHILADELPHIA, PENNSYLVANIA, ASSIGNORS TO AJAX METAL COMPANY, A CORPORATION OF PENNSYLVANIA.

RAILWAY JOURNAL-BEARING.

No. 846,397.

Specification of Letters Patent.

Patented March 5, 1907.

Application filed August 31, 1906. Serial No. 332,785.

To all whom it may concern:

Be it known that we, GUILLIAM H. CLAMER and CHARLES F. HOPKINS, both citizens of the United States, and residing in the city of Philadelphia, county of Philadelphia, and State of Pennsylvania, have jointly invented certain new and useful Improvements in Railway Journal-Bearings, of which the following is a specification.

This invention relates to railway journal-bearings, and it involves the shape or form of the bearing as well as the material of which it is made, both being coördinately important; and the object of the invention is to provide a bearing which shall be light and therefore comparatively inexpensive, yet possessed of sufficient mechanical strength and which shall be applicable for coöperation with the American Master Car-Builders' Association present standard box and wedge.

The nature, characteristic features, and scope of our invention will be more fully understood from the following description, taken in connection with the accompanying drawings, forming part hereof, and in which—

Figure 1 is a longitudinal central section of a journal-box and contained parts embodying features of the invention. Fig. 2 is a top or plan view of a bearing detached from the journal-box and embodying features of the invention. Fig. 3 is a side elevational view of the same. Fig. 4 is a transverse sectional view taken on the line 4-4 of Fig. 2; and Fig. 5 is a sectional view, on a reduced scale, of the wedge.

Internally the form of the bearing is semicylindrical, as at 1, and externally the form of the bearing is semicylindrical, as at 2. Upon the exterior of the bearing there are arranged semipolygonal flanges, of which three are shown, one, 3, being arranged at one end, another, 4, in the center, and the third, 5, at the other end. The three flat surfaces 6, 7, and 8 of these flanges, as well as the flat surface 9, of a longitudinally-ranging centrally-disposed flange 10, impart to the structure a generally semipolygonal back. The bearing

is shown as provided with the usual upturned flange 11 and with lateral extensions 12. The described bearing is constructed of manganese bronze or equivalent metal, which is relatively very hard and strong, and the bearing is internally faced with a bearing metal, as lead or lead alloy, which is relatively soft and weak.

The spaces between the rim and projections lighten the structure, so that comparatively little metal is required for making it, while at the same time the semipolygonal projections and the lengthwise-ranging rib and the material employed not only impart sufficient mechanical strength to the structure, but also give it the shape or form and dimensions requisite for mounting, fitting, and holding it between the journal 14 and the superposed wedge 15, which is provided with a semipolygonal face and is arranged inside of the journal-box 16, which is of the form prescribed as standard by the American Master Car-Builders' Association.

Having thus described the nature and objects of our invention, what we claim as new, and desire to secure by Letters Patent, is—

A bearing consisting of metals whereof one is relatively weak and soft and the other is relatively strong and hard and comprising a semicylindrical portion having upon its exterior semipolygonal projections arranged at and intermediate of its ends and having a centrally-disposed projecting rib, the upper faces of said rib and projections constituting a plain semipolygonal surface in combination with a journal-box for containing the bearing and with a wedge having a semipolygonal face and interposed between the journal-box and said semipolygonal surface, substantially as described.

In testimony whereof we have hereunto signed our names in the presence of two witnesses:

GUILLIAM H. CLAMER.
CHARLES F. HOPKINS.

Witnesses:

S. E. JUDGE,
J. CECIL BRIGHTBILL.
